US0D1017993S

(12) United States Design Patent (10) Patent No.: US D1,017,993 S
(45) Date of Patent: * Mar. 19, 2024

- (54) SHOE
- (71) Applicant: NIKE, Inc., Beaverton, OR (US)
- (72) Inventor: Shawn G. Carboy, Portland, OR (US)
- (73) Assignee: NIKE, Inc., Beaverton, OR (US)
- () Term: 15 Years
- (21) Appl. No.: 29/898,544
- (22) Filed: Jul. 28, 2023
- (51) LOC (14) Cl. 02-04
- (52) U.S. Cl. USPC D2/947; D2/954; D2/956
- (58) Field of Classification Search
- USPC D2/902, 906, 908, 916, 918, 925,

Primary Examiner — T Chase Nelson

(74) Attorney, Agent, or Firm — Banner & Witcoff, Ltd.

(57) CLAIM

The ornamental design for a shoe, as shown and described.

DESCRIPTION

FIG. 1 is a front perspective view of a shoe showing my new design;
FIG. 2 is a side view thereof; and,
FIG. 3 is a rear perspective view thereof.
The broken lines and unshaded areas depicting the remainder of the shoe form no part of the claimed design.

1 Claim, 3 Drawing Sheets
